UNITED STATES PATENT OFFICE.

CHARLES ASHTON HENRY BULLOCK, OF LONDON, ENGLAND.

PRINTING PRESS.

Application filed July 18, 1921, Serial No. 485,569, and in Great Britain September 16, 1920.

This invention relates to printing presses for printing preferably from type, or it may be used in connection with a stencil. The object of the invention is to provide a light portable press which may be operated by hand. The invention consists broadly of a printing press comprising an inking roller for inking the type, and a pressure roller for effecting the printing, the two rollers being so mounted that the operation of a reciprocable handle brings the inking roller into operation when the said handle is moved in one direction and brings the pressure roller into operation when it is moved in the reverse direction, and the invention further comprises certain features in the ink feeding arrangements and the method of feeding the ink from a fountain to the distributing roller and thence to the inking roller adapted to revolve over the type to supply the said type with ink on one operation of the reciprocable handle.

In order that the invention may be clearly understood and readily carried into practice, reference will now be made to the accompanying drawings which illustrate a press constructed in accordance with the preferred embodiment of my invention, and in which:—

30 Figure 1 is a perspective view thereof, Figure 2 shows an arrangement for adjusting the form or chase, and Figure 3 is an end elevation, part of the frame or support being removed for clearness.

35 Referring to the drawings the numeral 1 designates the support carrying the chase or form 2 in which the type or stencil is carried. The support 1 is preferably hinged at its bottom end to a bracket 3 secured to the base 4. By this means the press can be folded up and laid flat when not in use. When in action it stands upright at a suitable angle and is made unmovable by means of arms or standards 5 pivotally mounted at 6 to the support 1 and provided with slots 7 at the lower end, the arms being released when it is desired to fold up the press by unscrewing the nuts 8. A frame 9 is hinged at its extreme end 10 to a bracket on the base, this frame operates about the support 1 over which it swings. The frame 9 carries a rocking frame 11 in which are journaled two shafts 11^a and 12, and the frame 11 is journaled to oscillate in frame 9 on the shaft 13.

45 An inking roller 14 is carried on shaft 11^a

and a pressure roller 15 is carried on the shaft 12. Normally the inking roller 14 is held or retained in contact with the type during one operation or stroke of the arm 9, by means of a spring 16 on the shaft 13, one end of such spring being secured to an operating handle 17. The inking roller 14 is adapted to roll over an endless band 18 carrying the ink which feeds the roller. This endless band 18 is mounted upon two shafts 19 carried by a frame 20 secured in position and removable by means of nuts 21. A fountain 22 is provided on the frame 20, the said fountain carrying the ink which feeds the endless band 18. To secure more even distribution of the ink a second roller 23 is provided below the fountain and is free to revolve against the endless band.

At the upper end of the support 1 a transversely disposed actuating rod 24 is supported in a pair of curved slots 24' with the ends of this rod projecting beyond the support 1 in the path of movement of the swing frame 9. A cam plate 25 is pivoted on the rod 24 and is fashioned with a cam corner 25' and a cam slot 25^a, into which slot a guide pin 25^b protrudes, said pin being fixed on the support 1.

Means are provided for retaining the paper sheet in position for making the impression thereon; for opening and holding open said retaining means at the inking stroke to facilitate the insertion of a paper sheet; and for lifting the printed sheet from the form. For this purpose I utilize a somewhat U-shaped, pivoted, spring pressed frame comprising a pair of lifting plates 26 extending alongside the form, and hinged at 26' to the support 1. These side plates are connected by a transverse plate 26³ at the top of the device, and at the ends of the transverse plate are arranged a pair of spring clips 25² for gripping the paper sheet at its upper ends and holding it during the impression stroke or printing operation.

In operation of the press, assuming the parts are in the position shown in Figure 1 and the full line position Figure 3 the handle 17 is raised and rotates about the centre 10 and carries the inking roller 14 over the surface of the endless band and subsequently over the surface of the type, thus inking the type. As the arm 9 reaches the uppermost position of its stroke it engages the rod 24 which operates the cam plate 25, ar-

ranged on each side to move the paper support 26 to the position shown in dotted lines Figure 3, the corner 25¹ engaging a lip on the upper or gripper portion 25² of the paper support and opening it out as shown, against the action of a spring 26^a connected to the hinged plate 26^a, to facilitate the insertion of the paper which is subsequently held tightly by the gripper during the operation of printing. The same movement of the cam plates causes the inking roller to rock in an upward direction assuming the position shown in dotted lines Figure 3, whilst at the same time the pressure roller 15 assumes the desired position for the printing or downward stroke. A roller at each end of the inking roller runs over cams 27 near each end of the spring plate 26^a to lift the inking roller clear of the paper clip 26^b. By means of a trip action including a latch 28 pivoted on handle 17 the rocking bars 11 are retained in this position against the action of the spring 16 so that on the return stroke of the handle 17 the inking roller returns clear of the type, whilst the pressure roller 15 which on the upward stroke was clear of the type, returns on its return journey under the guide rails 29 secured at each side of the machine exercising sufficient pressure on the paper which has been inserted above the inked type, to give the requisite impression. When the operating handle 17 is passing the upper portion of the guide rail 29, the lip 28¹ on the trip action engages the corner 29¹ of the rail thus releasing the rocking shafts which when the pressure roller is clear of the guide rails enables the inking roller to again come into contact with the surface of the endless band. On completion of the downward or printing stroke the arm 9 contacts with and actuates a spring controlled lever 30 on which is mounted a ratchet and pawl mechanism. The toothed wheel 31 of the mechanism gears with the wheel 32 of the lower shaft 19 on the endless band. The endless band, by means of the gearing, is caused to travel forward a certain extent with each operation or impression so that the inking roller travels over a certain amount of fresh surface each time.

The chase containing the type can be brought nearer to or further away from the rollers, to regulate the amount of pressure, or allow for printing different thicknesses of paper. A convenient device for this purpose is shown in Figure 2, and it will be readily understood that on rotation of the nuts 33 causing movement of the pins 34 the cams 35 are operated and so raise or lower the form or chase 2 carrying the type 2¹ nearer or further away from the pressure roller.

As the frame 9 is swung upwardly, near the end of its up-stroke, it encounters the

laterally projecting end of rod 24, at the right in Figure 1. Continued movement of the frame 9 in contact with this end of the rod causes the rod to slide in slots 24' of the stationary frame 1. The rod carries 70 with it the cam plate 25 (Fig. 3) which is slotted at 25^a for co-action with a guide pin 25^b of the frame 1. This bodily movement of the cam plate causes its lower end to swing upwardly, and in its upward movement the plate which has one edge normally located beneath the lifting plate 26, swings the plate 26 as indicated in dotted lines, to open position to remove a printed sheet and to thereby permit insertion of another sheet in proper place on the form. The free arms of the clips 26^a are also swung on their pivots 26' by this movement of cam plate 25, as indicated by dotted lines in Figure 1 to release the printed sheet. 85

What I claim and desire to secure by Letters Patent is:

1. The combination in a foldable printing press having a base, of a hinged foldable frame and means for holding said frame in operative position, a handle-frame pivoted on the base, an oscillatable frame carried by said handle-frame and an inking roller and pressure roller journaled in the oscillatable frame, an inking device on the foldable frame, and means on said foldable frame for retaining a paper sheet in operative position for said rollers. 90

2. In a foldable printing press the combination with a base of a foldable frame hinged at one end of the base and a foldable-handle frame hinged at the opposite end of the base, pivoted brace members carried by the foldable frame and means for detachably connecting them to the base, an oscillatable frame journaled in the handle frame, an inking roller, and a pressure roller carried by said oscillatable frame. 100

3. The combination in a printing press with a base and stationary frame, of a pivoted handle frame, an oscillatable frame pivoted in the handle-frame, an inking roller and a pressure roller journaled in the oscillatable frame, a spring connecting the handle-frame and the oscillatable frame for holding the latter in position for operation of the inking roller, means for moving said oscillatable frame to operative position of the pressure roller, and a pawl on the handle-frame for co-action with the oscillatable frame for retaining said frame in the latter position. 110

4. The combination of a printing press with a stationary frame and base, of a pivoted handle frame and printing devices carried thereby, a spring pressed paper support pivoted on the stationary frame, actuating means on the stationary frame adapted to engage said support, and movable means on the stationary frame in the path 120

of movement of the handle-frame for operating said actuating means whereby the printed sheet is lifted.

5. The combination in a printing press with a stationary frame and base, of a pivoted handle-frame and printing devices carried thereby, a spring pressed paper support pivoted on the stationary frame, actuating means on the stationary frame adapted to engage said support, a movable rod supported in the stationary frame in the path of movement of the handle-frame and oper-

atively connected with said actuating means, and means for guiding said actuating means to lift the spring pressed support. 15

6. The combination in a printing press with a stationary frame and base, of a pivoted handle-frame and printing devices carried thereby, an endless inking band operatively supported on the stationary frame, and means actuated by said handle-frame for intermittently moving said band. 20

In witness whereof I affix my signature.
CHARLES ASHTON HENRY BULLOCK.
